RANGE

Arthur P. Schulz, Hinsdale, Ill., assignor to G. & J. Teller, Chicago, Ill., a partnership composed of Grace Teller and Jacob Teller

Application July 20, 1938, Serial No. 220,298

4 Claims. (Cl. 126—39)

This invention relates to cooking range construction, and particularly to the form of the gas cooking top wherein the arrangement of the burner controls is grouped in such manner that they are readily accessible at a substantially single position at the front of the range.

A further feature resides in a construction in which, as distinguished from the usual gas manifold which extends entirely across the front of the range, or in some models, just to the rear of a front plate, I provide a hollow casting arranged at the rear of the range, near the top, and in which the gas valves are grouped in such manner that the valve stems, associated with the handles at the front, may lie in grouped parallel relation, and extend transversely of the top beneath the cooking surface, at approximately the center line thereof.

A further feature resides in the particular arrangement of the mixer tube arms, whereby they may properly cooperate with the group arrangement of the gas controlling valves at the rear of the range.

A further feature resides in the construction wherein the cooking top may be formed in complete units; that is to say, a cooking unit may embody in a single device, a top surface, or a section thereof, the burner (which is of the converging type, forming the subject matter of a copending application), and the mixer tube arm.

The above and many other additional features and advantages will become apparent to those familiar with the art, upon references to the following specification and the accompanying drawings, in which

Fig. 1 is a top plan view of the range embodying my unified burner and group control thereof;

Fig. 2 is a horizontal section taken substantially on the line 2—2 of Fig. 1, with the burners shown in section;

Fig. 3 is a front elevation of the range top, looking in the direction of the arrow 3 in Fig. 1;

Fig. 4 is a front perspective view of a console type range embodying my invention;

Fig. 5 is a front perspective view of a combined coal and gas range to which my invention may be applied; and

Fig. 6 is a vertical sectional view of the range shown in Fig. 5, and substantially on the line 6—6 thereof.

Figs. 7 and 8 are top plan views similar to Fig. 1 respectively disclosing modified embodiments of the invention.

Referring more particularly to the drawings by numerals of reference, and especially to Fig. 55

ures 1 through 4, 1 indicates the body of the range, embodying our invention, it being recognized that the construction forming the subject matter thereof may have its application to any 5 of the well known types of range or stove now in use, and certain of which, by way of illustration are shown in the accompanying drawings.

As illustrated in the views in Figs. 1, 2 and 3, the idea is shown as applied for instance, to a console range, such as is shown in Fig. 4, the invention however, being directed to the burner and top structure, irrespective of the peculiar design of stove to which it is adaptable for use.

In Fig. 1, the low oven is shown at 2, the door therefor at 3, and the insulated cover at 4, the flue 5, provided by the under sheet of the cover and a spaced plate 6, being for the usual purpose of venting the oven to an outlet (not necessary to be shown) at the rear of the range. The oven door is provided with a suitable handle 8.

The cooking top, is as shown, formed by a pair of combined top plate and burner members, wherein the burners are indicated at 10 and the conduits cast as an integral part of the plate structure at 11.

The present structure, however, departs from the arrangement disclosed in the application referred to, to the extent that while employing the full idea therein proposed adapts it for use 20 in the peculiar manner as now described. The present invention contemplates, as distinguished from the more commonly known and used arrangement of gas burner mixer tubes, valves and handles disposed at some portion of the stove 25 at the front thereof in a straight line along the manifold, the grouping of both the valves and their associated elements and also the control handles, the former preferably at the rear and the latter at the front of the stove.

To this end, I provide each of the top burner plates 12 having the burner 14 and the cast in gas conduits 15, with a pair of parallel mixer tube arms 16 also preferably cast integral with the burner plate 12, and extending inwardly in 30 parallel relation with each other with the rear edge thereof, and terminating in mixer chamber 17, short of the inner side edge of the plate. Each of the mixer chambers 17 is provided with a pivotal air valve 18 controlling the air inlet 35 opening 19.

As shown in Figs. 1 and 2 especially, the two top burner plates are arranged with their longer and side edges in parallel relation and in substantial juxtaposition, the mixer tube arms of the respective plates extending in opposite di-

rections inwardly and toward one another, there being a space remaining between their opposed end portion. The burner plates are suitably mounted upon the top of the stove by a suitable rectangular framework 20.

Supported upon and at the rear of the stove as by bolts 21 is a shallow gas manifold box 22 with which communicates preferably at its lower side with a gas supply pipe 23 which leads to a suitable source of supply, not necessary to be shown. Mounted upon the top of the manifold box 22 in grouped relation are a plurality of gas valves 24 and 25, the former controlling the passage of gas to the oven, while the latter control the gas to the several burners of the top plate, through the mixer tube arms 16 respectively.

As shown in Fig. 2, the several valves 24 and 25, as well as the arms 16 are arranged in substantially the same horizontal plane, the valve bodies being supported by studs 26 communicating with the interior of the manifold box 22, and the valves being turnable on horizontal axes which are in parallel relation. The vertical axes of the several valve supporting studs 26 define a triangular outline, so that the valves are disposed in stepped or offset relation, permitting grouping within an area of small compass. This is illustrated more clearly in Figure 1, wherein the valve operating rods 27 connected with the several valves, are allowed to lie close to one another in parallel relation, and extend forwardly of the stove beneath the burner plates and into a valve handle casing 28 mounted upon the upper front central portion of the range.

The valve handle casing 28 is preferably of a general dome shape, its upper curved wall being provided with a plurality of slots 29 and 30 with which oscillate the stems 31 of the valve handles 32 and 33.

The valve operating rods at their forward ends extend through openings in the front upper frame member and in which they may have their front bearings, and into the casing 28. On the free end of each of these rods is mounted one of the valve stem handles above referred to, the outer of the rods carrying the handle 32 while the inner one carries the handle 33. To permit the arrangement, the dome is of stepped shape as shown in Fig. 1, so that the front valve handles are both forwardly and laterally offset with respect to the latter.

The rod 27 which controls the oven valve 24, and which is disposed between the two sets of rods which control the valves 25, extends through the valve handle casing 28 and has its forward bearing in the front wall 34 thereof, a valve handle 35 being fixed at its free end.

In the console style of range shown in Fig. 4, the supporting tubular metal framework is indicated at 36, the high oven at 37, splasher-back at 38 and utility compartment at 39, the latter closed by door 40 having handle 41. The valve control means is shown here generally at 42.

The structure illustrated in Figs. 5 and 6 embodies a combination gas and coal range, showing the adaptability of our invention to this type of cooking apparatus. In the present views, 43 indicates generally the body of the range, which includes the gas cooking top 44, the coal burner top 45, oven 46, with door 47, firepot 48 with door 49 and the grouped burner valve control assembly 50. The details of the general structure shown in these two figures form the basis of our

co-pending application, Serial No. 189,214, filed February 7, 1938.

In Figs. 7 and 8 are disclosed the adaptation of the invention to different arrangements of burners in the cooking top.

Fig. 7 shows the invention in operative association with four burners disposed in staggered or off-set relation while Fig. 8 shows the invention in operative association with four burners disposed in a straight line.

The structure of Fig. 8 being more nearly aligned with the structure of Fig. 1 than is Fig. 7, the structure of Fig. 8 will be first described.

As shown, the cooking top includes a pair of longitudinally aligned top plates 12a and a single plate 12b parallel with plates 12a, contiguous thereto, and of a length equal to the combined length of plates 12a.

Each plate 12a supports a pair of burners 14 with all of the burners in a straight line.

The mixer tube arms 16 supported by the opposed plates 12a extend toward each other and into operative association with the valves 24 and 25 in the same manner as in the construction disclosed in Fig. 1.

The valve operating means are similar to those of Fig. 1 and are designated by like reference characters, the description thereof however is not repeated.

The structure according to Fig. 7 includes a pair of angularly related top plates 12c each of which supports a pair of burners 14 with their centers substantially in the longitudinal center line of the plate, whereby the burners are in staggered relation.

The rectangular formation of the cooking top is completed by the supplemental top plates 12d and 12c.

In this form of the invention the valves 24 and 25 are operatively associated with a manifold 22a which together with the valves is concealed beneath the plate 12d.

The mixer tubes 16 are related to the valves as in Fig. 1 but the tubes are concealed and disposed substantially centrally of the cooking top.

The valve operating means are the same as in the structure of Fig. 1 except that the rods 27 are much shorter.

Thus while three specific burner arrangements are shown with the improved valve and valve operating arrangement operatively associated therewith, it is manifest that the invention is applicable to various other gas burner arrangements.

What I claim is:

1. In a gas range, a cooking top, a pair of burners arranged at each side of the transverse center line of the cooking top, a mixer tube arm in communication with each of the burners, the arms common to each pair of burners adjacent their free ends being parallel and in closely spaced relation, with corresponding ones of the two pairs of arms being axially aligned and with their free ends in spaced relation, a manifold disposed between the free ends of the arms, valves for controlling the flow of gas from the manifold to the arms, valve operating rods oscillatably mounted beneath the cooking top in closely spaced parallel relation and in a single horizontal plane, and handles connected with the respective rods disposed at the front of the cooking top adjacent said transverse center line and movable parallel with the front of the cooking top for oscillating said valve operating rods, said valves being arranged in triangular formation with the

apex of the triangle rearwardly from the front of the cooking top and wherein said handles are also arranged in triangular formation with the apex forwardly of the front of the cooking top for providing compact arrangement of the valve operating rods in parallelism and in a single horizontal plane.

2. In a gas range, a cooking top, a gas manifold of substantially triangular form in plane disposed below the cooking top and with its apex in the central transverse vertical plane of the cooking top, a pair of mixer tube arms having closely spaced parallel free end portions terminating adjacent the manifold at each side of said plane, a burner in communication with each of

5 said arms, valves for controlling the flow of gas from the manifold to the arms, valve operating rods disposed beneath the cooking top in closely spaced parallel relation and symmetrical to said plane, and handles disposed at the front of said cooking top and connected with the respective rods for oscillation of same in operating the valves.

10 3. The structure defined in claim 2 wherein said manifold is disposed intermediate the front and rear edges of the cooking top.

4. The structure defined in claim 2 wherein said manifold is disposed to the rear and externally of said cooking top.

ARTHUR P. SCHULZ.
